CARL E. ANDERSON, OF GRAND HAVEN, MICHIGAN.

PROCESS OF FORMING TURNBUCKLES OR THE LIKE.

1,413,821.

Specification of Letters Patent. Patented Apr. 25, 1922.

Application filed November 29, 1920. Serial No. 426,951.

To all whom it may concern:

Be it known that I, CARL E. ANDERSON, a subject of King Gustaf V of Sweden, residing at Grand Haven, in the county of Ottawa and State of Michigan, have invented certain new and useful Improvements in Processes of Forming Turnbuckles or the like, of which the following is a specification.

10 This invention relates to an improved method of forming an article of manufacture and particularly to a process of forming a turn-buckle. The principal object of the invention is to provide means for forming a turn-buckle from a single piece of sheet metal. Still another object is to provide a punching and drawing process of forming a turn-buckle from a single sheet of metal. Other objects relate to various features of 15 the process such as will appear more fully hereinafter.

The nature of the invention will be understood from the following specification taken with the accompanying drawings, in 20 which the article of manufacture in the various stages of its formation and the apparatus for performing the various steps of the process have been illustrated.

In the drawings—

30 Figure 1 shows a vertical section through a die punch machine, illustrating the first operation upon the sheet metal blank;

Fig. 2 is a vertical section through another form of die punch, illustrating the 35 operation performed on the article after it has been put into the form illustrated in Fig. 1;

Fig. 3 shows a vertical section through another form of die punch, illustrating the 40 method of operating upon the blank after it has been put into the form illustrated in Fig. 2;

Fig. 4 shows a plan view of the article after it has been operated upon by the mechanism 45 illustrated in Fig. 3;

Fig. 5 shows the article of Fig. 4 after it has been flattened out;

Fig. 6 shows the apparatus for shearing off the lateral edges of the article after it 50 has been put into the form illustrated in Fig. 5;

Fig. 7 shows a vertical section through a perforating punch and die for forming apertures through the ends of the cylindrical 55 projections of the turn-buckle; and

Fig. 8 shows a vertical section through a

punch and die for imparting a curved contour to each of the lateral walls of the turn-buckle.

The turn-buckle is formed from a single sheet of sheet steel or other metal of uniform thickness which is cut to form a blank of circular form. This circular blank is then operated upon by the mechanism illustrated in Fig. 1. This mechanism comprises a die holder 10 which is cut away on its upper side to form a cylindrical recess 11 adapted to receive an annular tension plate 12 which surrounds the center block 13. The tension plate 12 normally tends to move upwardly on the center block under the influence of the stripper pins 14 which extend downwardly through apertures in the die holder and are actuated by a spring in the usual manner. A blanking die 15 seats in an annular recess 16 formed in the upper surface of the die holder around the recess 11 and the inner annular wall of the blanking die is adapted to form a continuation of the annular wall of the recess 11. The sheet metal blank 18 of circular form is placed upon the center block 13 within the blanking die 15 and the lateral edges thereof are forced downwardly by means of an annular blanking and drawing punch 19 which is carried by the punch holder 20. A knockout punch 21 is mounted within the blanking and drawing punch 19 and is adapted to force the blank 18 downwardly against the center block 13. The stem 22 of the knockout punch extends upwardly through the punch holder and is capable of movement therein for the purpose of ejecting the blank from the drawing punch 19 after the blank 18 has been put into cup-shaped form, as illustrated in Fig. 1, by the operation of the mechanism.

The cup-shaped blank illustrated in Fig. 1 is then operated upon by the mechanism illustrated in Fig. 2 which comprises a die shoe 25 having an annular perforating die 26 mounted thereon. An annular gauge 27, having an internal diameter slightly greater than the internal tapered bore 26^a of the perforating die, is mounted on the die and is adapted to hold the cup-shaped blank in position to receive the perforating punch 28 which is carried by the movable punch holder 29. When the punch moves downwardly it cooperates with the die 26 to cut a circular slug 30 from the bottom of the cup-shaped blank, thus leaving a cylindrical

ring of metal 31 to be operated upon by the succeeding steps of the process. This apparatus comprises a die holder 32 adapted to support two sliding blocks 33 having 5 horns or punches 34 formed on the upper sides thereof and extending laterally in opposite directions. These horns are adapted to enter recesses 35 which are formed in sliding blocks 36 mounted above the blocks 10 33 and provided on their outer sides with inclined faces 36^a which are adapted to be engaged by the inner inclined faces 37^a of the cam blocks 37. A punch holder 38 carries a tapered punch or spreading tool 39 15 which is adapted to pass between the sliding blocks 33 and force them outwardly by coaction with their inner inclined faces 33^a, the central part of the die holder 32 being provided with an aperture 40 to receive the 20 lower end of the spreading tool upon the downward movement thereof. When the tool 39 moves downwardly a punch holder 38 engages the cams 37 and causes them to move the sliding blocks 36 inwardly in 25 opposition to the punches 34 formed on the blocks 33. The circular sheet metal article 31, as illustrated in Fig. 2, is placed in position with the lateral walls thereof extending around the projecting horns 34 and lying 30 within the sliding blocks 36. The downward movement of the spreading tool 39 and the corresponding movement of the punch holder 38 then operate to project the metal outwardly on diametrically opposite 35 parts of the sheet metal article to form substantially cylindrical projections 41, as illustrated in Fig. 4. The blocks 33 and 36 may be changed at different stages of the process so that the punches 34 and recesses 35 may 40 gradually be increased in depth as the process is carried on, thus gradually forming the projections 41 on opposite sides of the cylindrical article 31. After forming the article as illustrated in Fig. 4, it is placed in a press 45 and compressed in a plane at right angle to the cylindrical projections 41, thereby projecting it into the elongated shape 42 illustrated in Fig. 5, wherein the side walls lie substantially parallel to each other and 50 unite the opposite cylindrical projections.

After the article 42 has been formed into the shape illustrated in Fig. 5, it is operated upon by the mechanism illustrated in Fig. 6, wherein the die holder 45 is shown 55 supporting a die 47, the cutting edge of which is adapted to cooperate with the laterally extending projection 48^a of a punch 48 mounted in the punch holder 49. The article 42 is placed on the die with its lateral 60 edge lying parallel to and overlapping the cutting edge thereof, whereupon the downward movement of the punch operates to trim off a portion 50 of the lateral edge of the wall of the article, thus providing opposite parallel walls of uniform width.

In the next operation the article is operated upon by the mechanism illustrated in Fig. 7, where a die holder 52 is shown supporting a die 53 having a central tapered aperture 53^a. The partially formed article 70 is then mounted endwise on the die 53 with the end of one of its cylindrical projections registering with the aperture 53^a. A perforating punch 54 having a horn-like projection 54^a, is then moved downwardly within the article, thereby forming an aperture through the end wall of the cylindrical projection. 75

After the article has been operated upon by the mechanism illustrated in Fig. 7, it is further subjected to compression in the mechanism of Fig. 8. This apparatus comprises a die holder 55 having a die 56 mounted thereon and adapted to cooperate with a punch 57 carried by the punch holder 58. 80 The die 56 and the punch 57 are provided with cooperating inclined surfaces 56^a and 57^a, respectively, which insure the proper registration of the coacting parts when the punch moves downwardly. The turn-buckle 90 is placed in a depression 59 which is formed in the die and it is engaged by the walls of another depression 60 formed in the punch. When the parts come together these 95 walls of the depressions formed in the die and in the punch operate to impart a curved cross section to each of the lateral walls of the turn-buckle. After the lateral walls have been curved, the cylindrical projections 100 may be internally threaded if desired.

It will be apparent from the foregoing that I have provided a novel process of forming an article of irregular shape from a single sheet of metal by an improved method of punching and drawing the metal. 105 Although I have explained a particular application of the process to illustrate its use in forming a particular article of manufacture, it will be understood that it may be employed in various ways without departing from the scope of the appended claims. 110

I claim:

1. The process of forming a turnbuckle which comprises the operations of forming an annular sheet metal ring, and forming a substantially cylindrical projection in the wall of the ring. 115

2. The process of forming a turnbuckle which comprises the operations of forming an annular sheet metal ring, and forming substantially cylindrical projections on opposite sides of said sheet metal ring. 120

3. The process of forming a turnbuckle which comprises the operations of forming an annular sheet metal ring, forming substantially cylindrical projections on opposite sides of said sheet metal ring, and flattening said ring transversely to the longitudinal axes of said cylindrical projections. 125

4. The process of forming a turnbuckle 130

- which comprises the operations of forming a cup-shaped sheet metal article, cutting away the lower wall of said article, and forming diametrically cylindrical projections in the 5 annular wall of said article.
5. The process of forming an article of manufacture which comprises the operations of forming a cup-shaped sheet metal article, cutting away the lower wall of said article, 10 forming diametrically cylindrical projections in the annular wall of said article, and flattening said annular walls between said projections and transversely to the longitudinal axes of said projections.
- 15 6. The process of forming an article of manufacture which comprises the operations of forming a cup-shaped sheet metal article, cutting away the lower wall of said article, forming diametrically cylindrical projections 20 in the annular wall of said article, flattening said annular walls between said projections and transversely to the longitudinal axes of said projections, and forming apertures through the end walls of said projections.
- 25 7. The process of forming an article of manufacture which comprises the operations of forming a cup-shaped sheet metal article, cutting away the lower wall of said article, forming diametrically cylindrical 30 projections in the annular wall of said article, flattening said annular walls between said projections and transversely to the longitudinal axes of said projections, and trimming off the edges of the flattened walls extending between said projections.
- 35 8. The process of forming a turnbuckle which comprises the operations of forming an annular sheet metal ring, forming substantially cylindrical projections in the wall 40 of said ring, and imparting a curved transverse cross section to the wall of said ring between said cylindrical projections.
9. The process of forming a turnbuckle which comprises the operations of forming 45 an annular sheet metal ring, forming substantially cylindrical projections in the wall of said ring, imparting a curved transverse cross section to the wall of said ring between said cylindrical projections, and forming apertures through the end walls of said 50 projections.
10. The process of forming a turnbuckle which comprises the operations of forming an annular sheet metal ring, forming substantially cylindrical projections in the wall 55 of said ring, imparting a curved cross section to the wall of said ring between said cylindrical projections, forming apertures through the end walls of said projections, and internally threading said projections. 60
11. The process of forming an article of manufacture which comprises the operations of forming an annular sheet metal ring, forming substantially cylindrical projections extending outwardly on opposite sides 65 of said ring, pressing the walls of said ring into parallel relation to said projections, and forming apertures through the end walls of said projections.
12. The process of forming an article of 70 manufacture which comprises the operations of cutting a circular sheet metal blank, projecting said blank into cup-shaped form, cutting away the circular lower wall of said cup-shaped article, forming diametrically 75 opposite outwardly extending cylindrical projections in the annular wall of the article, pressing the curved walls of said article into parallel relation between said projections, trimming off the lateral edges of said 80 parallel walls, forming apertures through the end walls of said projections, and imparting a curved cross section to each of said parallel walls. 85

In testimony whereof, I have subscribed my name.

CARL E. ANDERSON.
